Primary Examiner — Catheri Oliver-Garcia(74) *Attorney, Agent, or Firm* — Mesmer & Deleault PLLC; Ross K. Krutsinger(57) **CLAIM**

We claim the ornamental design for a pouch for a battery of a cordless power tool, as shown and described.

DESCRIPTION

FIG. 1 is a right, rear perspective view of one embodiment of a pouch for a battery of a cordless power tool showing our new design with a connector retaining strap and a D-ring connector.

FIG. 2 is a right, front perspective view thereof.

FIG. 3 is a right side elevational view thereof.

FIG. 4 is a left side elevational view thereof.

FIG. 5 is a front elevational view thereof.

FIG. 6 is a rear elevational view thereof.

FIG. 7 is a top plan view thereof.

FIG. 8 is a bottom plan view thereof.

FIG. 9 is a right, rear perspective view of another embodiment of a pouch for a battery of a cordless power tool showing our new design with a connector loop.
FIG. 10 is a right, front perspective view thereof.
FIG. 11 is a right side elevational view thereof.
FIG. 12 is a left side elevational view thereof.
FIG. 13 is a front elevational view thereof.
FIG. 14 is a rear elevational view thereof.
FIG. 15 is a top plan view thereof.
FIG. 16 is a bottom plan view thereof.
FIG. 17 is a right, rear perspective view of another embodiment of a pouch for a battery of a cordless power tool showing our new design with a cord loop.
FIG. 18 is a right, front perspective view thereof.
FIG. 19 is a right side elevational view thereof.
FIG. 20 is a left side elevational view thereof.
FIG. 21 is a front elevational view thereof.
FIG. 22 is a rear elevational view thereof.
FIG. 23 is a top plan view thereof.
FIG. 24 is a bottom plan view thereof.
FIG. 25 is a right, rear perspective view of another embodiment of a pouch for a battery of a cordless power tool showing our new design with connector retaining strap, D-ring, and an optional pocket.

FIG. 26 is a right, front perspective view thereof.
FIG. 27 is a right side elevational view thereof.
FIG. 28 is a left side elevational view thereof.
FIG. 29 is a front elevational view thereof.
FIG. 30 is a rear elevational view thereof.
FIG. 31 is a top plan view thereof.
FIG. 32 is a bottom plan view thereof.
FIG. 33 is a right side elevational view of another embodiment of a pouch for a battery of a cordless tool showing our new design with optional vent holes in the side panels;
FIG. 34 is a left side elevational view thereof;
FIG. 35 is a right, rear perspective view thereof;
FIG. 36 is a top plan view thereof;
FIG. 37 is a bottom plan view thereof, showing the optional drain opening in the bottom panel; and,
FIG. 38 is a right, front perspective view of the pouch embodiment of FIG. 1 shown installed on the battery pack of a cordless power tool. The battery pack and power tool are illustrated in broken lines and form no part of the claimed invention.
